United States Patent Office

Des. 194,934
Patented Apr. 2, 1963

194,934

PLATE OR SIMILAR ARTICLE

Shigeru Masuda, Nagoya, Japan, assignor to Noritake
Co., Inc., New York, N.Y., a corporation of New York

Filed Mar. 13, 1961, Ser. No. 64,260

Term of patent 3½ years

(Cl. D44—15)

FIG. 1

FIG. 2

FIG. 1 is a plan view of a plate or similar article, showing my new design, a portion of the design being shown between dotted lines, and a repeat portion being shown between dot-and-dash lines, and

FIG. 2 is a view showing a segment of the design applied to a portion of the plate immediately beyond the concavity, to enlarged scale to show details of my design.

The plate is of a conventional configuration when viewed from the side and bottom thereof.

I claim:

The ornamental design for a plate or similar article, substantially as shown and described.
